[57] **CLAIM**

The ornamental design for a synthetic vascular prosthesis, as shown and described.

DESCRIPTION

FIG. 1 is a perspective view of a synthetic vascular prosthesis showing my new design;

FIG. 2 is a front elevation view thereof, the opposite side being substantially a mirror image of that shown;

FIG. 3 is a top plan view thereof;

FIG. 4 is a left side elevation view thereof;

FIG. 5 is a right side elevation view thereof;

FIG. 6 is a bottom view thereof;

FIG. 7 is a cross-sectional view taken along line 7—7 in FIG. 2;

FIG. 8 is a cross-sectional view taken along line 8—8 in FIG. 2; and,

FIG. 9 is a cross-sectional view taken along line 9—9 in FIG. 2.

Primary Examiner—Stella Reid
